Primary Examiner — Robert M Spear*Assistant Examiner* — Keith Frank(74) *Attorney, Agent, or Firm* — Marshall, Gerstein & Borun LLP(57) **CLAIM**

The ornamental design for film used to make packages, as shown and described.

DESCRIPTION

The FIGURE is a plan view of a repeating pattern on film used to make packages. The film has a minimal thickness.

The evenly spaced broken lines on outer edges of the FIGURE and forming a closed curved shape in the central part of the FIGURE represent boundaries of the claimed design. The other evenly spaced broken lines represent environmental features that do not form part of the claimed design. The dash-dot broken lines represent score lines in the film.
